UNITED STATES PATENT OFFICE.

ANDREW D. WYCKOFF, OF OAK PARK, ILLINOIS, ASSIGNOR TO OIL PRODUCTS APPLI-
ANCE CO., OF MAYWOOD, ILLINOIS, A CORPORATION OF ILLINOIS.

LIQUID-DISPENSING DEVICE.

Application filed August 2, 1922. Serial No. 579,088.

To all whom it may concern:

Be it known that I, ANDREW D. WYCKOFF, a citizen of the United States, and a resident of Oak Park, county of Cook and State of Illinois, have invented certain new and useful Improvements in Liquid-Dispensing Devices, of which the following is declared to be a full, clear, and exact description.

This invention relates to liquid dispensing devices and its principal object is protection of the device against the inclemencies of the weather. The invention has especial application to oil tanks, such as are in common use at garages and filling stations. As is well known, oil tanks are provided with pumps for withdrawing and dispensing the oil, and a great deal of annoyance and loss of oil is occasioned, because the oil continues to drip from the discharge nozzle, after the measure or container into which the oil is delivered, has been removed from beneath the nozzle. Various devices have been designed to catch the dripping oil and return it to the tank, but these are at best unsatisfactory, or impracticable, and liable to get out of repair, and are otherwise objectionable. Rain is apt to enter the oil return devices, or dust and dirt, or other foreign particles are apt to enter the tank through the return tube. Moreover, when springs are employed for automatically returning the drip tube to a position in which it catches the dripping oil, snow or ice is apt to gather on the spring and interfere with the operation of the device.

With the use of a dispensing device embodying the present invention, these objectionable features are eliminated. The invention consists in the several novel features, hereinafter fully set forth and claimed.

The invention is clearly illustrated in the accompanying drawing, in which:

Fig. 1 is a side elevation, partly broken out, of a liquid dispensing device, embodying a simple form of the present invention; Fig. 2 is a plan thereof partly broken away; Fig. 3 is a fragmentary side elevation of the discharge nozzle and return tube; Fig. 4 is a detail, vertical, cross section, taken on line 4-4 of Figure 1; Fig. 5 is a detail, horizontal section, taken on line 5-5 of Fig. 1; and Fig. 6 is a perspective view of a fragment of the drip tube.

Referring to said drawing, which illustrates one embodiment of the present invention,

the reference character 7 designates a fragment of an oil tank, and 8, the base of an oil pump 9, which is mounted on the tank and has an arm 10, terminating in a nozzle 11, through which the oil is discharged. The pump 9 and discharge arm 10 are of conventional form, but the nozzle 11 contains novel features forming part of the present invention. Below the nozzle is mouth 12 of the drip tube 13, which leads to a return pipe 14 that is secured in the base 8 and discharges into the tank. The drip tube 13 is swiveled, or rotatively mounted upon the return pipe 14, whereby it may be swung from a position, with its mouth under the discharge orifice of the nozzle 11, to a position in which it does not obstruct the flow of oil from the nozzle into a measure or other container placed below the nozzle. In the form of the invention illustrated, the drip tube 13 inclines downwardly from its mouth 12, and has a pipe 15 on its lower end, which protrudes into the return pipe 14. The upper end of said return pipe 14, is held in a hollow boss or lug 16, which projects laterally from the pump body, and located in a recess 17 in said boss 16 is a coiled spring 18, which surrounds the pipe 14, and engages at one end with the boss, and at the other end with the drip tube, the tension of the spring being exerted to turn the drip tube 13 in the direction of the arrow in Fig. 2, and thereby return it to effective position below the nozzle, whenever the drip tube is released from any other position. On the lower end of the drip tube 13, is a flange or cover 19 which overlies the boss 16, and completely covers the recess and spring, thereby preventing rain, snow, dust or other foreign particles from entering said recess or return pipe 14. To more effectively guard against the entrance of water or other foreign matter, the flange 19 has a down turned annular bead 20 which overhangs an upturned bead 21 on the boss 16. The flange 19 rests on the return pipe 14 or boss 16, and a pin or stud 22 secured in the pump body above the flange 19 prevents displacement or removal of the drip tube from the return pipe.

The nozzle 11 has a neck portion 24 which is attached to the arm 10, and it has a spout 25, which has a discharge orifice 26 in its lower end. The mouth 12 of the drip tube 13 flares upwardly as a preference, to a

place, when its edge 27^a is immediately below the discharge orifice 26. One half of its upper edge is free to swing under the spout 25 (see Fig. 4), but one side 27 of the mouth is preferably extended upward beyond said edge so as to stand along side of the spout, when in the position shown in full lines in the drawing. Extending over the mouth 12 are semi-circular flanges 28, 29, which are formed on said spout, and completely cover the open mouth 12; the flange 28 is placed close to the upper edge 27^a of the mouth, and has a down turned rim 30 which surrounds the immediate portion of the mouth below the edge 27^a, and the flange 29 is placed close to the upper edge of the extension 27 of the mouth, and as a preference has a down turned rim 31 on its edge. Connecting the flanges 28, 29 are vertical webs 32 that radiate from the body of the spout 25, and if desired said webs may have ribs 32^a along their outer edges that overlap the upright edges of the mouth extension 27. It is readily apparent from the above, that rain, snow, sleet, or other foreign substances, are kept out of the drip tube, while the mouth of the drip tube is held underneath the nozzle. Furthermore, the webs 32 act as a stop against which the spring 18 holds the mouth extension 27, thereby locating the mouth centrally under the spout, whereby any oil dripping from the spout will be carried back into the tank. If desired, a fine mesh wire screen 33 may be placed in the passage in the mouth to interrupt large particles.

In use the spring 18 yieldingly holds the mouth of the drip tube underneath the spout of the nozzle as heretofore explained. A person desiring to draw off a quantity of oil swings the drip tube away from the nozzle, either with his hand or with the measure or container which is to be filled, and holding the drip tube away from the nozzle with the measure. Such a position of the drip tube is illustrated by the dotted lines in Fig. 2. The pump is then put into operation and the desired quantity of oil drawn off into the measure. As the measure is removed from beneath the nozzle, the spring swings the drip tube back beneath the nozzle with the mouth completely covered by the flanges 28, 29, protected against the entrance of foreign substances, and in position to catch and convey back to the tank any oil that drips beneath the spout.

More or less variation of the exact details of construction is possible without departing from the spirit of this invention; I desire, therefore, not to limit myself to the exact form of the construction shown and described, but intend, in the following claims, to point out all of the invention disclosed herein.

I claim as new, and desire to secure by Letters Patent:

1. In a liquid dispensing device, a tank having an oil dispensing arm and nozzle, said nozzle having a discharge spout and a rain shedding cover thereon adapted to overhang the mouth of a drip tube, an oil return drip tube rotatively mounted on said tank and having a mouth adapted normally to stand underneath said spout and cover, and a discharge end emptying into the tank, and means for moving the mouth of said drip tube underneath said spout and cover, when released from any other position. 70 75

2. In a liquid dispensing device, a tank having an oil dispensing arm and nozzle, said nozzle having a discharge spout, and upper and lower lateral flanges, forming covers, an oil return drip tube rotatively mounted on said tank and having a mouth adapted to stand under said spout, and a discharge end emptying into said tank, said mouth having an upward extension located at one side of said spout, and said upper flange of the nozzle, covering said extension, 85 90 and said lower flange covering the remainder of the mouth, and means for moving said drip tube underneath said spout and covers, when released from any other position.

3. In a liquid dispensing device, a tank having an oil dispensing arm and nozzle, said nozzle having a discharge spout, formed with a flange serving as a cover for the mouth of a drip tube, and having a semi-circular down turned rim, a return drip tube 100 rotatively mounted on said tank, and having an open mouth adapted to normally stand under said spout and cover, said drip tube having a discharge end discharging into said tank, and a spring engaging said drip tube, 105 for holding the mouth of said drip tube underneath said spout and cover.

4. In a liquid dispensing device, a nozzle formed with a spout having an upper semi-circular flange and a lower semi-circular 110 flange, said flanges being disposed on opposite sides of the spout and connected by vertical webs, and a spring returned drip tube having a mouth adapted to stand under said spout, and formed with an upward extension 115 along the side of said spout, said flanges and webs serving to close said mouth when the latter is held under the spout.

5. In a liquid dispensing device, a pump base, an oil return pipe secured in said base and open at its upper end, a return drip tube, a discharge pipe secured to said drip tube and projecting down therefrom and entering said return pipe, a support in which said tube is rotatively mounted, there being a 125 recess in said support, a coiled spring in said recess engaging said drip tube, and a cover flange on said drip tube covering said recess in said support and covering said return pipe. 130

6. In a liquid dispensing device, an oil return pipe, a drip tube having a cover flange on its lower end, and a discharge pipe projecting down therefrom into said oil return pipe, a recessed support for the upper end of said oil return pipe, the recess and oil return pipe being covered by said flange cover, and a coiled spring in said recess, one end of which engages said drip tube.
7. In a liquid dispensing device, a pump base, an oil dispensing arm extending up from said base and having a nozzle terminating in a discharge spout and having a rain shedding cover thereon for a drip tube, an oil return drip tube rotatively mounted on
- 5
6. In a liquid dispensing device, an oil return pipe, a drip tube having a cover flange on its lower end, and a discharge pipe projecting down therefrom into said oil return pipe, a recessed support for the upper end of said oil return pipe, the recess and oil return pipe being covered by said flange cover, and a coiled spring in said recess, one end of which engages said drip tube.
7. In a liquid dispensing device, a pump base, an oil dispensing arm extending up from said base and having a nozzle terminating in a discharge spout and having a rain shedding cover thereon for a drip tube, an oil return drip tube rotatively mounted on
- 10
8. In a liquid dispensing device, a return drip tube, a pump base on which said tube is rotatively mounted, an oil return pipe secured in said base, said tube entering said return pipe, a coiled spring for rotating said tube and a cover on said drip tube for covering said spring and oil return pipe.
